UNITED STATES PATENT OFFICE.

JOHN E. BELL, OF NEW YORK, N. Y.

STEAM-GENERATOR.

1,184,302.

Specification of Letters Patent. Patented May 23, 1916.

Application filed August 4, 1911. Serial No. 642,360.

To all whom it may concern:

Be it known that I, JOHN E. BELL, a resident of New York, in the county of New York and State of New York, have invented a new and useful Improvement in Steam-Generators, of which the following is a full, clear, and exact description, reference being had to the accompanying drawings, forming part of this specification, in 10 which—

Figure 1 is a longitudinal vertical section showing a preferred form of my boiler; Fig. 2 is a horizontal section on the line II—II of Fig. 1; Fig. 3 is a vertical transverse section through the furnace chamber looking toward the boiler tubes at one side; Fig. 4 is a side elevation; Fig. 5 is a view similar to Fig. 1, showing a modified form; Fig. 6 is a detail enlarged cross section 20 showing the baffle arrangement of Fig. 5; Fig. 7 is a view similar to Fig. 1, showing another modified form; and Figs. 8 and 9 are detail views of a regenerator brick which I prefer to employ.

25 My invention is designed to provide an entirely new type of boiler and furnace therefor.

Heretofore, in the working of boilers, the fuel has been burned on a grate and the 30 major portion of the heating surface has absorbed sensible heat from the gases of combustion, and only a small portion of the heating surface has been exposed to the heat radiated directly from the burning fuel, or the highly heated brickwork of the 35 furnace lining, which is much more rapidly absorbable. The temperature of the waste gases leaving the boiler has been from twenty to one hundred and fifty degrees 40 more than the temperature of the steam, under the best conditions, and a great amount of heat is lost on this account.

In my invention I preferably expose the 45 major portion of the heating surface of the steam generator to the radiant heat of the fuel, and abstract the sensible heat of the gases of combustion by the use of regenerators or recuperators, which return this heat to the air entering the furnace, increasing the temperature of combustion. The 50 proportion of the heat of combustion appearing as radiant heat rapidly increases with the temperature and is practically all absorbed directly by the heating surface. 55 The area of the heating surface can on this

account be reduced to a fraction of that heretofore used. The theoretical lower limit of the temperature of the waste gases will be the temperature of the atmosphere and not the temperature of the liquid contained 60 by the heating surface as in boilers as now made.

In carrying out my invention, I utilize, in whole or in part, the following important features: first, the arranging of the boiler-heating surface so that the major portion thereof is exposed to the radiant heat of the burning fuel; second, the use of granulated or pulverized fuel which is burned in the form of a curtain or sheet. Third, the suspending of the burning granulated or pulverized fuel in air which is preheated by means of the furnace gases in a regenerator or a recuperator; fourth, the dropping of the granulated or pulverized fuel by gravity 75 through a furnace chamber or chambers in the form of a curtain; fifth, the inclosing by the regenerator of at least a part of the boiler; sixth, the use of a divided furnace having up and down passes, so that the ash 80 of the pulverized or granulated fuel burned in suspension will drop at the turn in the furnace.

The burning of the fuel while in suspension is an important feature. This does 85 away with the difficulty of grates which, even if water-cooled, would present enormous difficulties on account of the preheating of the air and the high temperature obtained. It also enables the boiler to absorb 90 directly a large amount of the radiant heat of the coal burnt in the curtain or sheet form, the coal acting as its own radiator and being a good radiator for this purpose. The size of the particles of coal and the temperature 95 of the air supply will regulate the time of combustion, other things being equal. With the high air temperature obtained by the regenerative or recuperative system, the fuel will be completely consumed during its vertical passage. A sheet 100 of the burning fuel will thus be formed through the length of the furnace, making a large radiating surface directly in front of the boiler-heating surface. Such combustible gases, distilled from the fuel, as are not consumed in the furnace will be burned in the passages leading to the regenerator or in the regenerator itself, and since the 105 température of the gases entering the re- 110

generator is high the combustion will be complete.

The drop of the granulated or pulverized fuel by gravity affords a simple and efficient means of burning the particles in suspension in a sheet or curtain form. The use of a down and up pass provides for dropping of the ash after the burning of the descending sheet or curtain of flame, and the partial inclosing of the boiler by the regenerator system will aid in preventing losses by radiation and also afford a more compact and efficient system.

I claim as advantages for my invention compared with boilers and furnaces as now made: (1), an increase in economy; (2), a reduction in first cost; (3), a reduction in space occupied; (4), a reduction in the cost of attendance; (5), the greater maximum capacity possible with a single unit.

In the drawings, referring to the form of Figs. 1 to 4, inclusive, the boiler heating surface consists of two banks of tubes 2 spaced apart from each other, each bank shown as consisting of two rows. These vertical tubes extend up into two parallel steam and water drums 3; and in order to provide cooler down-coming tubes, I preferably inclose certain of the tubes in fire brick, shown at 4, to make these tubes cooler than the others in this back row. This fire brick shields these tubes both from radiant heat and from the hot gases. The tubes of the two rows are preferably staggered so that each row will receive radiant heat from the burning curtain of fuel in front. Water circulating tubes 3 may be employed between the water spaces of the steam and water drums, and the mud drums may also be connected, if desired.

The front and rear of the boiler setting is formed by fire brick walls 5 and 6, which also inclose regenerators at the sides of the boiler. The boiler furnace chamber is divided by the fire brick partition 7, depending from the roof between the steam and water drums, and terminating above the ash pit 8. This partition may be supported on water boxes 9, having pipes 10 leading from their ends to the mud drums. Upwardly extending tubes may also be provided for these water boxes, as shown at 11. In this form, the powdered or granulated fuel is fed in through two long thin passageways 12, which extend the length of the furnace from front to rear and connect to a common chamber 13 provided with a swinging gate valve 14 by which the coal may be shunted to either side and hence fed into either of the channels 12. The coal is fed into this chamber 13 through chute 15, from hopper 15, controlled by rotary gate feed 16. These parts preferably extend from front to rear of the boiler.

Back of the two rows of tubes are the

walls 17 parallel with these rows, and extending from the mud drums 18 upwardly and terminating below the steam and water drums. These walls form the inner walls of a regenerator chamber shown as divided into three parts 19, each filled with fire brick tile of any desirable form. These flues communicate at their bottom with the chamber 20, which also connects with the lower end of the other regenerator pass containing two flues 21 filled with tile or castings. At the top of the flues 21 is a chamber 22 having a valved opening 23 to the outer air, and an opening 24 to the stack controlled by valve 25. The chamber above the flues 19 is closed in by a suitable fire brick roof 26, and the construction is the same on both sides of the boiler.

In the operation of this boiler, the powdered coal is fed down at one side of the central partition, this being the right-hand side of Fig. 1, with the valves in the position shown. At the same time the air passing through the down and up passes of the right-hand regenerator meets the coal in the upper part of the furnace in front of the boiler tubes, and the coal burns in a descending curtain or sheet in front of the tubes, which, being exposed to the radiations from this burning fuel, rapidly absorbs heat. On reaching the lower end of the furnace partition 7 the ash drops into the pit and the hot flame and gases sweep up on the left-hand side of the partition and subject the tubes therein to radiant heat and also partially to heat by convection. On reaching the top of the left-hand wall 17, the gases then flow downwardly and upwardly through the left-hand regenerator, heating the tile therein and passing to the stack. On reversal of the valves, the coal feed is also reversed, so that the dropping sheet of burning coal will be fed down through the left-hand half of the boiler furnace, the hot air entering the left-hand regenerator and joining the sheet, and the hot product passing out through the right-hand regenerator whose valves have been reversed.

The partition wall 7 will absorb heat on the side exposed to the radiations from the burning fuel and will radiate heat to the boiler heating surface on the other side, and thus acts as a secondary radiator. Cooled in this way its temperature is prevented from rising to a dangerous point.

In Fig. 4 I show a cylinder 27 having oppositely extending piston rods connected to link motion devices 28, by which the valves for each regenerator are simultaneously actuated to close the air valve of one and open the air valve of the other and at the same time open the stack valve of the first and close the stack valve of the second, and shift the coal feed.

In Fig. 5 I show another form of the in-

vention, where the boiler consists of two banks of tubes 2^a, with a large number of rows in each bank. The first and second rows adjacent to the furnace are staggered 5 in position, and support between them a tile baffle 30, which forms with the first row of tubes the furnace wall. The tubes are shown as curved at their ends and expanded into top and bottom drums 31 and 32, the 10 steam drums being connected by water-circulating tubes 33. The mud drums may also be interconnected, if desired. The walls 30 extend from the steam and water drums down to a level short of the mud drums, 15 and the center wall 34 extends upwardly from the ash pit short of the tops of the tubes. The coal feeder is substantially the same as in the first form, and the dampers may be arranged in the same manner. With 20 the dampers set as shown, the air will be drawn into the right-hand portion of the regenerator, and leaving the regenerator will pass down through the right-hand bank of tubes to the bottom of the baffle 30. During 25 this time the air heated by the regenerator will transmit a portion of its heat to the boiler tubes, the air then rising on the left-hand of the partition 34. The temperature will be raised during this pass on account 30 of the high temperature of this partition, and the air will then join the fuel fed in the sheet through the left-hand portion of the furnace. Combustion will occur in the sheet form in the left-hand part of the 35 furnace, and the gases of combustion will pass up through the left-hand bank of tubes into the regenerator and thence to the stack. The bank of tubes through which the hot gases pass will generate the bulk of steam. 40 though the other bank by cooling the heated air and by absorbing radiation from the central furnace wall will also produce steam. In this case the major part of the heating surface is not exposed to the radiating heat 45 of the fuel. This design is preferably used where the fuel is either oil or gas, in which case, of course, the coal feed would be dispensed with.

In Fig. 7 I show another modified form 50 wherein the water tubes 2^b form the casing of the furnace in the form of a rectangle. The upper ends of alternate tubes are bent outwardly and inwardly to enter the top and bottom headers 35 and 36, thus enabling 55 the two to be brought close together to form a gas-tight wall. Above the headers, tubes 37 lead to the steam and water drums 38, which extend from the front to the back of the setting, these tubes 37 having spaces 60 between through which air enters the furnace from the regenerators. The coal feed apparatus 39 in this case is located centrally between the drums, and drops a long sheet 65 of fuel through the center of the rectangular combustion chamber. The regenerator is

divided in two parts, as in the other cases, and placed half on one side and half on the other side of the boiler furnace. Each part is also shown as divided into two passes. In this case I employ fire brick 70 valves 40 which control the flues 41 and 41^a leading respectively to the top of the furnace and to the ash pit 42 below it. The regenerator valves 43 are shown as arranged to open and close both the stack and air 75 ports, and in the form shown air is entering the left-hand regenerator, this heated air entering through port 41 and joining the descending sheet of fuel. The tubes are exposed to the radiant heat, and the hot gases 80 passing into the ash pit rise through passage 41^a and pass in through the right-hand regenerator and thence to the stack. On reversing the valves, the flow of air and gases 85 will be reversed. The valves 40 are, of course, shifted simultaneously with the top regenerator valves.

In Figs. 8 and 9 I show the type of thin regenerator brick which I prefer to employ, although any type of regenerator brick or 90 castings may be employed.

The advantages of my invention result from the use of regenerators in connection with the high utilization of radiant heat. A boiler in which radiant heat alone was 95 used would not be efficient, since the sensible heat of combustion would be lost, whereas I utilize this to heat the regenerators, this heat being in turn transferred to the incoming air. A very high temperature may thus be 100 obtained, and the radiant heat effectually utilized.

As the high temperature attained would seriously affect grates, even if water-cooled, I overcome this difficulty by doing away 105 with grates and burning the granulated or powdered fuel in suspension. This is also highly efficient for producing radiant heat on account of the long flame in sheet or plate form which gives a high radiation effect. 110 The preheated air is utilized to aid in suspending as well as in burning the sheet of fuel, which is preferably dropped by gravity, although I do not restrict my claims to this method of introducing the fuel as it 115 may be suspended in a lateral or uprising current of air. The regenerator may be built above ground, and advantages obtained by partially inclosing the boiler with the regenerator, since further heat is imparted 120 by radiation to the boiler and the loss from radiation of the boiler setting is reduced.

Many changes may be made in the form and arrangement of the boiler, regenerators, the means of burning the fuel, &c., without departing from my invention, since I consider this type of boiler and furnace to be broadly novel. I have used the term boiler as meaning an arrangement of surface or 125 surfaces for absorbing heat and transmitting 130

ting it to a contained or enveloped fluid. The surfaces may be composed of tubes, as shown in the drawings, or of plates or drums, etc. The fluid may be water, as in ordinary boilers, steam as in a superheater, or any liquid required to be heated or vaporized.

By the term "radian heat" as used herein, I refer to the initial heat radiations of the burning fuel.

I claim:

1. A water tube boiler having a combustion chamber inclosing at least a portion of the heating surface of the water tubes, means for supplying granulated or pulverized fuel to said chamber and burning it in suspension therein, whereby said heating surface is directly exposed to the radiant heat of the burning fuel, and means for utilizing the heat of the outgoing gases beyond the said heating surface for preheating the air which supports the combustion of the fuel in said chamber, substantially as described.

2. A water tube boiler having a combustion chamber inclosing at least a portion of the heating surface of the water tubes, means for supplying granulated or pulverized fuel to said chamber and burning it in suspension therein, whereby said heating surface is directly exposed to the radiant heat of the burning fuel, and a regenerator or recuperator beyond the said heating surface for abstracting a portion of the sensible heat of the gases of combustion and returning the same to the air supply for said combustion chamber, substantially as described.

3. A boiler having water heating surfaces, a vertically extending combustion chamber which incloses at least a portion of the heating surfaces, means for feeding granulated or pulverized fuel vertically through said chamber and burning it therein while falling, whereby said heating surfaces are directly exposed to the radiant heat of combustion of the burning fuel, together with means for utilizing the heat of the outgoing gases beyond the heating surface of the generator for preheating the air which supports combustion in said chamber; substantially as described.

4. A boiler having water heating surfaces, a vertically extending combustion chamber, a portion of the heating surfaces being exposed in the combustion chamber, means for feeding a vertical sheet of powdered or granulated fuel in the form of a curtain or sheet along the exposed heating surfaces in said chamber and burning it therein while in suspension whereby said exposed portions of the heating surfaces are directly exposed to the radiant heat of the burning fuel, together with means for utilizing the heat of the outgoing gases from the combustion chamber beyond the heating surface of the

generator for preheating the air which supports the combustion in the combustion chamber; substantially as described.

5. A boiler having water heating surfaces, a vertically extending combustion chamber which incloses at least a portion of the heating surfaces, means for feeding granulated or pulverized fuel vertically through said chamber and burning it therein while in suspension whereby said heating surfaces are directly exposed to the radiant heat of the burning fuel, and means for utilizing the heat of the outgoing gases from the combustion chamber beyond the heating surfaces of the generator for preheating the air which supports the combustion in said chamber; substantially as described.

6. A boiler having water heating surfaces, a vertically extending combustion chamber which incloses at least a portion of said heating surfaces, means for feeding granulated or pulverized fuel vertically through said chamber and burning it therein while in suspension whereby said heating surfaces are directly exposed to the radiant heat of the burning fuel, and regenerators arranged to preheat air by the products of combustion and supply the same to the fuel; substantially as described.

7. A boiler having water heating surfaces, and means for feeding granulated or pulverized fuel to cause it to fall by gravity along said surfaces, and for causing the fuel to burn while passing along said surfaces, together with regenerator means arranged to preheat air by the products of combustion and supply the same to the fuel; substantially as described.

8. A boiler having water heating surfaces, a vertically extending combustion chamber which incloses at least a portion of the heating surfaces, means for feeding pulverized or granulated fuel to cause it to fall by gravity along said surfaces, a regenerator at least partially inclosing the combustion chamber for preheating air, and means for supplying said preheated air to the combustion chamber; substantially as described.

9. A boiler having water heating surfaces, a vertically extending combustion chamber which incloses at least a portion of the heating surfaces, a reverse pass in said combustion chamber arranged to drop the ash, and means for feeding pulverized or granulated fuel to cause it to fall by gravity along a portion of said heating surfaces and for causing the fuel to burn while passing along said surfaces in combination with regenerators arranged to preheat the air supplied to the combustion chamber by the outgoing products from said chamber; substantially as described.

10. A boiler having water heating surfaces, a vertically extending combustion chamber which incloses at least a portion of

- the heating surfaces, a dividing wall within said combustion chamber forming up and down passes, and means for feeding granulated or pulverized fuel vertically through 5 one of said passes and burning it therein while in suspension, whereby said heating surfaces in said pass are directly exposed to the radiant heat of the burning fuel, in combination with regenerators arranged to 10 preheat the air supplied to the combustion chamber by the outgoing products from said chamber; substantially as described.
11. In a steam generator, means for causing pulverized or granulated fuel to fall by gravity through a combustion chamber, 15 water-heating surfaces forming at least a portion of the walls of the said chamber, and means for burning the fuel in sheet or curtain form adjacent to said surfaces, whereby the latter are directly exposed to the initial radiations of the burning fuel, together with a regenerator arranged to utilize the hot gases 20 passing from the combustion chamber for heating the air supplied to said combustion chamber, substantially as described.

heat the air supplied to the combustion chamber by the outgoing products from said chamber, substantially as described. 25

12. In a steam generator, means for causing pulverized or granulated fuel to fall by gravity through a combustion chamber, water-heating surfaces forming at least a portion of the walls of said chamber, means 30 for burning the fuel in sheet or curtain form adjacent to said surfaces, whereby the latter are directly exposed to the initial radiations of the burning fuel, together with a regenerator arranged to utilize the hot gases 35 passing from the combustion chamber for heating the air supplied to said combustion chamber, substantially as described.

In testimony whereof, I have hereunto set my hand.

JOHN E. BELL.
